UNITED STATES PATENT OFFICE.

ALBERT H. SPELLMEYER, OF ST. LOUIS, MISSOURI.

COMBINED BEVERAGE AND WATER COOLER AND DISPENSER.

1,238,842.

Specification of Letters Patent.

Patented Sept. 4, 1917.

Application filed August 17, 1916. Serial No. 115,401.

To all whom it may concern:

Be it known that I, ALBERT H. SPELLMEYER, a citizen of the United States, and resident of St. Louis, Missouri, have invented certain new and useful Improvements in Combined Beverage and Water Coolers and Dispensers, of which the following is a specification containing a full, clear, and exact description, reference being had 5 to the accompanying drawings, forming a part hereof.

My invention relates to improvements in "combined beverage and water coolers and dispensers," and the primary object of my 15 improvement is to construct as a unit the body portion of the device, which body portion comprises a receptacle for water, a receptacle for ice, and a plurality of receptacles for flavoring extracts or beverages; 20 such a body portion having provisions made for a ready attachment of drawing faucets.

With the above object in view my invention consists of certain novel details of the construction and arrangement of parts 25 which will be clearly, concisely and fully set forth in my specification and specifically pointed out in my claims, and illustrated by the accompanying drawings in which—

Figure 1 is a front elevation of a device 30 constructed, according to my invention, with certain of the drawing faucets removed.

Fig. 2, is a plan of the device with a portion of the removable cover broken away, the "original" packages or bottles not being 35 shown.

Fig. 3, is an enlarged detail sectional elevation showing one of the flavoring or beverage receptacles, its drawing faucet, and a portion only of a bottle or "original" pack- 40 age.

Fig. 4, is a sectional plan taken on the line 4—4 of Fig. 5.

Fig. 5, is a sectional elevation taken on the line 5—5 of Fig. 2, the drawing faucet of 45 the water receptacle being removed.

Fig. 6, is a perspective of one of the gaskets forming a seat for a bottle.

Fig. 7, is an inverted plan of the removable cover; and

Fig. 8, is a detail sectional elevation showing a stopper employed in lieu of a bottle.

Referring by numerals to the accompanying drawings, 10 designates vertical walls constituting the body of the device; these 55 walls are substantially vertical, and as

shown in my drawings may flare downwardly and outwardly adjacent the bottom of the device. Removed from the lowermost margin of the cylindrical body 10, is the bottom proper 11, which is horizontally 60 disposed and having its margin integrally united with the inside face of the wall 10; arising from the uppermost face of the bottom proper 11, is a cylindrical wall 12, which arises to a height less than the wall 65 10, of the body proper. The lowermost edge of the cylindrical wall 12, is integrally united with the uppermost face of the bottom proper 11.

The space 13, within the wall 12, is utilized 70 as an ice receptacle, and the space 14, between the walls 12 and 10, is utilized for water, which is cooled by contact with the wall 12 of the ice receptacle 13.

The water receptacle as shown as a drawing faucet 15, which is inserted through an opening 16, formed in the wall 10, of the body portion next the bottom proper 11. It is pointed out here that the construction of the faucets shown forms no part of my invention, and I wish to be understood as not limiting myself to the use of any particular form of faucet.

The reference numeral 17, designates a flange which is horizontally disposed and 85 extends inwardly flush with the top of the body proper, and for only a portion of the circumference thereof, as clearly shown in Fig. 2, and formed through the flange preferably equi-distantly spaced circumferentially of the flange is a number of openings 18, and upstanding from the flange surrounding each opening is a bead 19.

The reference numerals 20, designate the body portions of the flavoring or beverage 95 receptacles these bodies are, as clearly shown in Fig. 4, of substantially U-shape in cross-section, and their lengths as clearly shown in Figs. 3 and 5, are equal to the spacing of the flange 17, and the bottom 100 proper 11. Each of the body portions 20, is separately formed and its free side margins, as well as its upper and lower ends are integrally united with the body portion of the device, the said free ends of the receptacles being united with the wall 10, the lower ends of the receptacles with the bottom proper and the upper ends with the flange 17, the receptacles registering with the openings 18.

It is here pointed out that the wall 10, the bottom proper 11, the wall 12, the flange 17, and the receptacles 20, are integrally united and form a single unitary structure. This 5 unitary structure is composed entirely of earthen-ware and in substantially the following manner:

- The substantially cylindrical wall 10, constituting the body of the device, is "spun." 10 the bottom proper is then formed by rolling and spinning, and while the earthen-ware is still in an "unset" or "semi-plastic" condition, its bottom is united with the inner surface of the wall 10, usually by the addition 15 of earth in a plastic condition and somewhat more moist than the wall 10, and bottom 11. The wall 12, is then formed by spinning as an open ended cylindrical tube, and while still "unset" this lowermost margin 20 is united with the upper face of the bottom proper and of course while the bottom proper is still "unset," and its joint is preferably made by the addition of earthen-ware a trifle more moist than wall 12, and bottom 11. 25 The flange 17, is first formed and then its uppermost margin secured to the inner face of the wall 10, next its top; the securing being done by uniting its margin to the wall 10, before both become set and by the addition 30 of earthen-ware at the joint, which is slightly more moist than the flange and the wall.

The receptacles 20, are then formed by rolling and from a form bent into U-shape 35 and while still "unset" united with the wall 10, bottom 11, and flange 17, while all of said parts are still "unset" and by the addition of moist earthen-ware.

It will be obvious from the foregoing description that the entire body of the device 40 is a unitary structure having no joints. This unitary structure after having been thoroughly dried is then enameled over all of its surfaces, thereby making a structure which 45 is easily cleansed and in which there are no crevices for the lodgment of any liquid or foreign substance.

Adjacent the bottom end of each of the receptacles 20, there is provided as clearly 50 shown in Fig. 3, a drawing faucet 21, the specific structure of which forms no part of my invention and of course I do not wish to be limited to the form of faucet shown.

In each of the openings 18, in the flange 55 covering the receptacles 20, there is a gasket 22, which is inserted into the opening and hangs from its horizontal flange, as clearly shown in Fig. 6; there is formed in the gasket a groove 23, so that when a vessel 60 such as a bottle 24, a portion only of which is shown in Fig. 3, is inserted through the gasket, there will be provided a vent allowing escape of air when the liquid from the bottle is being supplied by gravity to the 65 receptacle 20. It being understood that the

flow of liquid from the bottle is limited by the height of the column of liquid in the receptacle 20, covering the mouth of the bottle.

When it is desired to employ in connection with this device carbonated water, a coil 70 75 80 85 90 95 100 105 110 115 120 125 130 135 140 145 150 155 160 165 170 175 180 185 190 195 200 205 210 215 flow of liquid from the bottle is limited by the height of the column of liquid in the receptacle 20, covering the mouth of the bottle.

When it is desired to employ in connection with this device carbonated water, a coil 25, is placed in the ice receptacle 13, its one end 26, leading to a source of carbonated water, while its other or upper end terminates in a faucet 27, in order that the water contained in the space 14, between the walls 10 and 12, which is to be used for drinking purposes, may be kept from contacting and being fouled by the metallic pipe and couplings of the tube 25, and faucet 27, there is provided a notch 28, in the wall 12, so that the drinking water will overflow into the space 13, before it reaches the plane of the pipe coupling between the coil and faucet.

In order to permit the placing and removal of the coil the stem 29, of the faucet is made of a length to extend inwardly beyond the flange 17 of the body and the upper end of the coil approximates the end of the stem 29, and is coupled thereto by a union 30.

It is thus obvious that when the union 30, is removed from the arm of the coil projecting toward the stem 29, the coil may be lifted upwardly without contacting with the flange 17.

Secured in the bottom proper 11, there is a drain pipe 31, having connection with a pipe 32, leading to any convenient point of discharge.

The reference numeral 33 designates a removable lid or cover for the entire body, whose edges overlap a portion of the flange

2. A beverage and water cooler and dispenser, comprising a unitary ceramic structure having an ice chamber, a water chamber surrounding the ice chamber, syrup receptacles within the water chamber and spaced from the ice chamber and each other, said receptacles having a wall coincident with the outer wall of the water chamber and said receptacles extending to the top of the dispenser, and a bottle neck receiving gasket

in the top of each receptacle having a vent therein.

In testimony whereof, I have signed my name to this specification, in presence of two subscribing witnesses.

ALBERT H. SPELLMEYER.
